CLOTHES-WASHING MACHINE

Leo M. Kahn, New York, N. Y.

Application April 16, 1943, Serial No. 483,230

3 Claims. (Cl. 68—23)

1

This invention relates to laundry machinery, and more particularly to a washing machine.

It is among the objects of my invention to provide a laundry machine of the above nature which is simple, inexpensive and sturdy in construction, and which is capable of carrying out all of the laundry operations of washing and extracting with a minimum amount of trouble, and at the same time with a high degree of efficiency.

Other objects will be in part apparent, and in part pointed out hereinafter.

The invention accordingly consists in the features of construction, combination of elements and arrangement of parts, all as will be exemplified in the structure hereinafter described, and the scope of the application of which will be indicated in the following claims.

In the drawing, wherein I have shown one form of my washer and extractor,

Figure 1 is a fragmentary sectional elevation showing the washing attachment in place on the machine base;

Figure 2 is a fragmentary sectional elevation taken along the line 2—2 of Figure 1;

Figure 3 is a sectional elevation taken along the line 3—3 of Figure 1;

Figure 4 is an enlarged fragmentary sectional elevation taken along line 4—4 of Figure 3; and

Figure 5 is a diagrammatic view of the interlock between the extractor clutch and the machine transmission.

The principal structural features of my washing machine are shown in Figures 1—5. Thus, as shown in Figure 1, the machine is shown with the table leaves 85 and 86 and drops 87 and 88 folded. Base frame 22 (Figure 1) has pivotally connected thereto a pair of fulcrum arms 139 and 140 which, as shown in Figure 2, are pivotally attached to lugs 141 fastened to the frame. These arms may be pivoted to the position shown in Figure 1, through suitable slots 142 formed in the center section 81 of the platform, wherein their upper ends are horizontally aligned (see Figure 1) and are accordingly in proper position to receive a pair of lugs 143 and 144 (Figure 2) fastened to the bottom of the washer tank generally indicated at 145. Washer tank 145 (Figure 1) has fastened to the bottom thereof a pair of hooks 146 and 147, the latter of which detachably carries the upper end of a spring 148, the lower end of which may be secured to a pin 149 or the like secured to one of base legs 21. When spring 148 is attached to hook 147 on the washer tank, it biases the tank about its pivotal axis toward the position shown in Figure 1. Hook 146 de-

2

tachably carries the upper end of a short spring 150, the lower end of which is connected to a chain 151. The lower end of this chain is connected to one end of a lever 152 which may be pivoted as by a detachable pin about the axis of any one of several holes 153 formed in the bottom of a depending strut 154, the upper end of which is fastened to base frame 22. The other end of lever 152 is connected by a link 155 to a short post 156 secured to and extending from the lower end of plunger 35 so that when plunger 35 moves up and down upon rotation of cam 34, lever 152 is rocked about its pivot and accordingly tank 145 is rocked about its pivotal axis formed by the fulcrums 139 and 140. The amount of pivotal movement imparted to washer tank 145 may be varied by adjusting the pivotal axis of lever 152 between a maximum when the right-hand hole 153 is chosen, and a minimum when the left-hand hole 153 is chosen. If desired, the right-hand end of lever 152, as viewed in Figure 1, may carry a suitable follower (not shown) adapted to extend into a positive cam slot (not shown) cut in or formed on the left-hand face of cam 34, in which event

springs 148 and 150 and chain 151 may be dis-

pensed with and a rigid link (not shown) used to

connect the tank with lever 152. It will now ap-

pear that when the motor switch (not shown) is

closed, motor 30 operates continuously, and ac-

cordingly washer tank 145 (Figure 1) rocks back

and forth continuously until the switch is opened.

It is preferable, however, that plunger 35 be in

its down or solid line position, as shown in Figure

1, when washer tank 145 is installed or removed

from the machine.

It will be noted that tank 145 is provided with a door 158 through which access may be had to a drum generally indicated at 159 in which the soiled clothes are placed, or through which the drum, together with its contents, may be in-

stalled in the tank or removed therefrom. Also,

tank 145 is provided with suitable openings, such

as a soap inlet 160, a fresh water inlet 161 and

a drain 162. Suitably secured to the bottom of

tank 145 are a pair of L-shaped sections or tracks

163 (Figure 2) and 164 which, as better shown in

Figure 3, are properly spaced to act as guides for

drum 159 as it rolls back and forth through the

tank.

At the opposite ends of tank 145 (Figure 1) I preferably provide opposed pairs of elevating and stopping guides or tracks 165 and 166 which coact with trunnions or hubs 167 and 168 on the drum (Figure 3) to raise the drum and stop its

movement at the end of its travel in the tank, thus

preventing the drum from banging against the ends of the tank. Guides or elevators 166 serve a further purpose, which will be described hereinafter. Tank 145 (Figure 1) preferably includes opposed depresser plates fastened to opposite sides of the tank, one of which is shown at 169. These guides 169 overlie drum trunnions 167 and 168 for all positions thereof within tank 145, and accordingly assure proper travel and rotation of the drum through the tank and prevent its floating therethrough as the tank rocks.

It will now appear that as tank 145 rocks back and forth about its pivotal axis, by means of the mechanism heretofore described, drum 159 is caused to roll back and forth through the tank so that the soiled garments in the drum are tumbled about and accordingly thoroughly washed during the operation of the tank. To facilitate the tumbling of the clothes within drum 159, I preferably provide a suitable number of ribs or elongated projections 170. Also, drum 159 has a suitably hinged and latched door 171 through which clothes may be placed in or removed from the drum.

When it is desirable to use the washer described as an extractor, tank 145 is stopped in the position shown in Figure 1. The tank and drum 159 may thereupon be opened, as described, to permit access to a movable partition 172 (Figure 3) which is placed in the full line position shown when drum 159 is being used as a washer, but which may be moved to the dotted position when the drum is to be used as an extractor. Partition 172 may be held in its dotted line position by suitable lugs 173 or the like, fastened to the inner periphery of the drum, and which ride through slots 172a and 172b when the partition is moved over. This movement of the partition crowds the wet clothes into the confined area defined by the partition in its dotted line position and the left-hand side of the drum, as viewed in Figure 3, in which area the clothes may be evenly distributed so as to impart a better balance to the drum and accordingly cut down vibration upon rapid rotation thereof. As shown in Figure 3, the left side of drum 159 has a more or less conical plate secured thereto while the left-hand surface 172a of partition 172 is similarly shaped, thus facilitating the even distribution of the wet clothes about the inner periphery of the drum. It might be noted that partition 172 may be maintained in its full line position by a pair of lugs 174 similar to lugs 173. When it is desired to move the partition from one position to another, it is merely necessary to rotate it until its lugs 172a register with that pair of the lugs involved, whereupon the partition may be slid past the lugs and then rotated slightly to lock the partition back of the lugs. The partition is provided with suitable openings or slots, through which ribs 170 (Figure 1) extend, sufficiently wide to permit this partial locking or unlocking rotation of the partition. Also, springs 148 and 150 advantageously operate as vibration dampeners during extracting rotation of the drum.

As shown in Figure 4, hub or trunnion 167 of drum 159 is provided with a plurality of holes 175 to receive pins 176 fastened to and extending from a plate 177 mounted on the right-hand end of a short shaft 178 which is axially movable within a sleeve 179 rotatably mounted in a bearing 180 fastened to the side of tank 145. Sleeve 179 has an annular slot 179a formed therein, in which is disposed a spring 180 which biases shaft

178 to the right, i. e. in a direction to cause a driving connection between plate 177 and tank hub 167 by the insertion of pins 176 on the plate in holes 175 in the hub. Adjacent the left-hand end of shaft 178 is a pin 181 which extends through the shaft and is accordingly rotatable therewith relative to sleeve 179 until the pin registers with a slot 182 formed in the left-hand end of the sleeve. When the pin and slot thus register, spring 180 forces shaft 178 to the right, drawing pin 181 into slot 182 and accordingly effecting a driving connection between shaft 178 and sleeve 179. It should be noted that the inner end, i. e. the right-hand end of sleeve 179 is outwardly flanged as at 179a, while the left-hand end of the sleeve carries a nut 179b, the flange and nut thus clamping the sleeve in place within its bearing 180.

The extreme left-hand end of shaft 178 has a pulley 183 fastened thereto and this pulley is connectable with a driving pulley 184 (Figure 1) by a removable belt 185. Thus it will appear that when pulleys 184 and 183 are connected, and pulley 184 is driven, drum 159 is rotated, assuming that there is a driving connection between plate 177 and drum hub 167 (Figure 4).

As drum 159 (Figure 1), when full of wet clothes is somewhat heavy, it would be difficult properly to position it so that hubs 167 and 168 (Figure 3) would be coaxially aligned with shaft 178 and pulley 184. (It should be noted that hub 168 is connectable with a supporting shaft generally indicated at 186 in the same manner that hub 167 is connectable with shaft 178.) When the tank 145 is in its Figure 1 position, elevator guides 166 raise drum 159 to a position wherein the drum axis almost coaxial with the axis of pulley 183 (Figure 3) thus rendering it easy to connect the tank hubs 167 and 168 with shafts 178 and 186. It will be noted (Figure 4) that the axes of pins 176 are slightly above the axes of their corresponding holes 175 when plate 177 and hub 167 are separated. Also the ends of the pins are preferably rounded. Thus when the pins enter their respective holes the hub and accordingly the drum are raised by an amount equal to the axial displacement of the pins and holes so that hub 167 does not rub against guide 166 when the drum is rotated. The other drum hub 168 (Figure 3) is similarly raised from its guide 166.

It will now appear that drum 159 is readily convertible into an extractor and upon operation of pulley 184 (Figure 1) it may be rapidly whirled, thus to force the water out of the wet clothes therein in the usual manner. However, when drum 159 is used as an extractor, the driving connection which causes tank 145 to rock back and forth should be disconnected, and accordingly I have provided an interlock which precludes the rocking of the tank during extracting rotation of the drum. To this end I have shown in Figure 5 motor 30 which has a clutch 187 provided with a clutch lever 188 pivotally connected by a link 189 to one arm 190 of a bell crank lever pivoted as at 191. The other arm 192 of the bell crank is rigidly fastened to an operating arm 193 having a handle 194 which is readily accessible to the operator of the machine.

Operating lever 193 (Figure 5) is pivotally connected as by a link 195 to a lever 196 extending from transmission 32 and adapted in one position to disconnect the transmission from the washer driving mechanism and in another position to connect the transmission to the washer

driving mechanism. This linkage is so arranged that when operating lever 193 is rocked counter-clockwise, clutch lever 188 is rocked clockwise and transmission lever 196 is rocked counter-clockwise. This movement of the clutch and transmission levers engages clutch 187 and disconnects transmission 32 so that the extractor driving pulley 184 is driven and the washer driving mechanism is disconnected. Similarly, clockwise movement of operating lever 193 disengages clutch 187, but effects a driving relation between transmission 32 and the washer operating mechanism.

As many possible embodiments may be made of the above invention, and as many changes might be made in the embodiments above set forth, it is to be understood that all matter hereinbefore set forth or shown in the accompanying drawing is to be interpreted as illustrative and not in a limiting sense.

I claim:

1. In a laundry machine, in combination, a support, an elongated tank rockably mounted on said support, means in said support connected to said tank for rocking said tank, a drum disposed in said tank for rolling movement from one end of the tank to the other as the tank is rocked, means at each end of said tank for limiting the movement of said drum therewithin, and means for locking said drum at one end of said tank.

2. In a laundry machine, in combination, a support, an elongated tank rockably mounted on said support, means in said support connected to said tank for rocking said tank, a drum disposed in said tank for rolling movement from one end of the tank to the other as the tank is rocked, means at each end of said tank for limiting the movement of said drum therewithin, and guard means for restraining said drum from rising from its operative path as it rolls through said tank.

3. In a laundry machine, in combination, a support, an elongated tank rockably mounted on said support, means in said support connected to said tank for rocking said tank, a drum disposed in said tank for rolling movement from one end of the tank to the other as the tank is rocked, means at each end of said tank for limiting the movement of said drum therewithin, means for locking said drum at one end of said tank, and means forming a driving connection between said tank rocking means and said drum for rotating said drum when it is in said locked position.

LEO M. KAHN.
